UNITED STATES PATENT OFFICE.

NEWTON H. BOLTON, OF MINNEAPOLIS, MINNESOTA.

LATH-STRIPPING MACHINE.

SPECIFICATION forming part of Letters Patent No. 764,106, dated July 5, 1904.

Application filed June 16, 1902. Serial No. 112,000. (No model.)

To all whom it may concern:

Be it known that I, NEWTON H. BOLTON, a citizen of the United States, conducting business at No. 166 Western avenue, in the city of

5 Minneapolis, county of Hennepin, and State of Minnesota, have invented new and useful Improvements in Lath-Stripping Machines, of which the following is a specification.

10 My invention relates to lumbering; and it consists in improvements in sawing-machines used in the production of laths, which improvements are more fully described herein-after.

15 In the production of laths waste from the logs (slabs) are generally used. These are cross-cut by a machine designed for that purpose into blocks four feet long, which blocks are in turn divided longitudinally by another machine into planks about one and one-half 20 (1½) inches thick, technically called "bolts," which bolts in turn are subdivided longitudinally by still another machine into slats about three-eighths (⅓) of an inch thick, technically called "laths." Thus three different machines 25 are employed in the production of laths—viz., the crosscut-saw, which converts the slabs into "blocks," the lath-bolter, which converts the blocks into bolts, and the lath-stripper, which converts the bolts into laths.

30 My present invention relates to the last-named machine, the lath-stripper; and it consists, first, in an improved gage for guiding the bolts in their course to and the laths in their course from the saws; second, in improved pressure-feed rolls, and, third, in improved means for preserving parallelism of the feed-roll shafts, all of which is hereinafter fully described.

35 My invention is illustrated in the accompanying drawings, in which—

Figure 1 is a front elevation; Fig. 2, a side elevation; Fig. 3, a rear elevation; Fig. 4, a top view; and Fig. 5, a detail view, on an enlarged scale and partly in section, of a portion 45 of the machine.

Similar letters refer to similar parts throughout the several views.

A is the frame; B, the arbor; C, the saws; D, the table; E, the guide; F, the feed-roll mechanism, and G the driving-shaft.

The frame A, arbor B, and saws C are not unlike those commonly used, and as they form no part of my invention I do not deem it necessary to describe them herein.

55 The table D is an important feature of my invention. It consists of a horizontal bar *a*, having a longitudinally-extending upwardly-turned flange *b*. The horizontal portion *a* is mounted upon and supported by the vertical adjusting-bolts *c*, which bolts are secured to 60 its under side, extend downward therefrom, and pass loosely through a flange or ledge *d* of the frame A. These bolts (preferably four in number) are furnished with adjusting-nuts *e*, through the use of which the table D is 65 adjusted to height.

The guide E is another important feature of my invention. It consists of a horizontal bar resting upon the horizontal portion of the 70 table D and adjustably affixed to the vertical or flange portion *b* thereof, the manner of its attachment thereto being a novel feature. This guide E is laterally pierced intermediate its length, having a hole (preferably) midway between its opposite ends and two other holes, 75 one near each of its ends. These holes are threaded, thereby adapting them to receive the stud-bolts *f*, which bolts are screwed into the said guide from its rear side (the side toward the flange *b*) and each provided with two adjusting-nuts *g* and *g'*. The flange *b* of the 80 table D in like manner is laterally pierced—that is to say, is pierced horizontally—the three perforations therein being in register (in line) with the lateral perforations in the guide E. 85 These holes are not threaded, but are large enough to receive the threaded stud-bolts *f* freely. In effecting the attachment of these parts (the guide E and flange *b*) the outer adjusting-nuts *g* are removed from the bolts *f* 90 and those portions of the said bolts extending outward and beyond the remaining nuts *g* passed through the laterally-pierced flange *b*, when the adjusting-nuts *g* are replaced thereon. The part E (the guide) is now arranged 95 parallel with the part *b* (the flange) and the adjusting-nuts *g'* screwed up against both sides of the flange *b*, after which the adjusting-nuts *g* and *g'* of the middle bolt *f* (the one midway between the ends of the guide E) remain un-

10

disturbed. In adjusting the guide E the nuts g' of the end bolts f are respectively loosened, and the nuts g , impinging the front side of the said flange, are tightened, thereby deflecting either end of the said guide E, (through its flexibility,) the ends being thus sprung rearward, thus giving the guide E "clearance."

The feed-roll mechanism F is still another important feature of my invention. It consists of the frames h , mounted upon and (to a degree) laterally adjustable upon the larger or main frame A; the boxes or bearings i , located and vertically adjustable within the said frames h ; the shafts j and j' , journaled in and vertically movable with the said boxes i ; the stud-bolts k , affixed in the said boxes i and extending upward therefrom through the upper sides of the said frames h ; the clamp-nuts l , screwed upon the said stub-bolts k ; the vertically-pierced brackets m , affixed to the inner side walls of the said frames h ; the threaded rods n , passing loosely through said brackets and having their threaded ends extending upward and downward through the said brackets m ; the coiled springs o , encircling the said rods n , said springs resting upon the upper sides of the nuts on the said lower end of said rods, the upper ends of the springs bearing against the lower sides of the said brackets m ; the laterally-pierced horizontal bar p , mounted upon the upwardly-extending threaded stud-bolts k of the boxes i ; the upwardly-extending rods n ; the clamp-nuts q , screwed upon the said upwardly-extending stud-bolts k and the said rods n , and the feed-rolls r , affixed upon the said shafts j . The purpose of this construction is to automatically give a pressure upon the feed-rolls q , thus equalizing their pressure upon bolts of varying thickness. It will readily be seen that the tension of the springs o may be changed (increased or decreased) by turning down or turning up the clamp-nuts q .

The means for preserving parallelism of the feed-roll shafts j is yet another important feature of my invention. It consists in pivotally affixing one end (preferably the rear end) of one of the feed-roll frames h to the larger or main frame A by slotting the holes through which the bolts pass that secure the frame h to the main frame A and by providing the lateral adjustment of its opposite end, (the front end,) which lateral adjustment is effected by means of the horizontal adjusting-bolts s . This bolt, like the vertical adjusting-bolt c , is threaded throughout the greater part

of its length. It is passed loosely through a lug t , affixed upon the frame A, and is screwed into the laterally pierced and threaded side wall of the frame h . It is furnished upon each side of the lug t , through which it passes, with an adjusting-nut u , through the use of which the forward end of the frame h may be drawn toward or forced from the said lug t , thereby adjusting the feed-roll shaft j and bringing it into parallelism with its fellow feed-roll shaft j' . The adjustment of these adjusting or clamp nuts u is substantially as described in connection with the vertical adjusting-bolts c and the horizontal adjusting-bolts f and needs no repetition.

The driving-shaft G extends through the frame longitudinal, and hence parallel, with the feed-roll shafts j and j' . It is furnished intermediate its length with the band-wheel v and at its rear end with the pulley w . A driving-belt x transmits accelerated motion to the pulley y on the saw-arbor B, and a similar belt x' transmits retarded motion to the band-wheels z on the feed-roll shafts j and j' .

Having thus described my invention, what I claim as new, and desire to secure by Letters Patent, is—

1. In a lath-stripping machine, the combination with the frame adapted to support the working parts, an arbor journaled and rotatable therein, saws mounted upon and rotatable with the said arbor, a feed-roll for forcing the bolts forward to the said saws, clearing-rolls for carrying the laths away from the said saws, of the feed-roll mechanism F embodying the stud-bolts k affixed in the boxes carrying the shafts of the said rolls, the horizontal bar p through which the said bolts k extend, and the springs o intermediate the said frame and the said horizontal bar substantially as shown, and for the purpose specified.

2. In combination with the saws and the means for operating the same, a pair of frames, bearings adjustably mounted in said frames, feed-rolls journaled in said bearings, and bars extending across the top of said frames and being connected with the bearings arranged therein, means for adjusting said bars, bolts or rods extending through the said bars and springs encircling said rods, substantially as and for purpose specified.

NEWTON H. BOLTON.
